UNITED STATES PATENT OFFICE.

PARKER R. BRADLEY, OF EAST ORANGE, NEW JERSEY, ASSIGNOR TO AIRCRAFT FIRE-PROOFING CORPORATION, OF NUTLEY, NEW JERSEY, A CORPORATION OF NEW JERSEY.

METHOD OF FIREPROOFING AIRCRAFT.

1,309,453.

Specification of Letters Patent.

Patented July 8, 1919.

No Drawing.

Application filed December 22, 1917. Serial No. 208,447.

To all whom it may concern:

Be it known that I, PARKER R. BRADLEY, a citizen of the United States, and a resident of East Orange, in the county of Essex 5 and State of New Jersey, have invented a new and Improved Method of Fireproofing Aircraft, of which the following is a full, clear, and exact description.

This invention relates to the method of 10 and means for fireproofing inflammable parts of aircraft and the like, and the invention has to deal particularly with an improved protective covering for the inflammable parts, whereby gasoline or other 15 fuel spread over the wing or frame surface by backfiring of the motors, or otherwise, may burn if ignited by explosive incendiary bullets without the fire consuming the surface on which the fuel burns, so that it 20 is possible for the aircraft to be brought back to the earth without danger to the aviator or passengers.

The method broadly consists in applying 25 one or more coats of a fireproof liquid to the fabric parts to be protected, and after the coat or coats have dried, one or more coats of a suitable dope are applied and also one or 30 more coats of dope are applied to the wood-work, and after drying of the dope an adhesive or stickum dope is applied to the already 35 coated part, and finally a suitable metal foil is laid smoothly on the surface coated with the adhesive. If the foil-covered surface is exposed to the weather, a final coating of 40 spar varnish or the like may be employed. The fireproofing solution herein proposed fireproofs the fabric but the foil fireproofs the dope which is applied to the fabric or other parts of the flying machine. One or 45 more coats of dope may be applied to the foil, and then one or more coats of waterproof varnish applied to this coating of 50 dope on the foil.

The method is applicable to the wood-work 45 as well as to the linen, cloth or other fabric constituting the wing surface, except as to the woodwork the fireproofing liquid is omitted. Preferably the linen or other fabric is fireproofed before it is put on the 50 wing frame and while it is in long lengths. Almost any form of coating or dyeing machine may be resorted to for immersing the linen in the fireproof liquid, and after being immersed the cloth travels slowly 55 through a dry box until it is thoroughly

dry; or other equivalent means may be employed for this purpose. This immersing step in the process may be repeated any number of times.

The fireproofing liquid is made as fol- 60 lows:

28 ounces of ammonium phosphate
3½ ounces of boric acid
7 pints of water.

65

Sodium tungstate, sodium acetate or other chemicals having an equivalent action may be used.

When it is desired to fireproof a completed wing the sections of the wing can be 70 fireproofed by the method herein described by resorting to dipping and drying the sections by any suitable machine designed for that purpose. This has reference to the applying of the various liquid coats but 75 the metal foil is laid carefully on the surface.

When the fireproofed linen, wood framework of the wings and other parts of the aircraft are thoroughly dry four or more 80 coats, preferably of cellulose acetate or acetyl cellulose dope, are applied either by hand labor or by dipping, and when this dope is dry an adhesive or stickum dope is applied to the surface, and while the adhesive 85 is still sticky the foil is laid. In laying the foil the adhesive dope is applied to only a small part of the surface to be protected at a time, and a section of foil is then laid on the sticky adhesive, and after being carefully rubbed down so as to 90 be perfectly smooth, the paper backing on which the foil is carried is pulled off and thrown away, and then another strip or section is applied in the same manner, the 95 joints between the sections being preferably overlapped, although when two layers of foil are employed the sections are so laid that the second layer covers the joints of the sections forming the first layer. When 100 the foil overlies the woodwork of the frame the foil may be tacked down by very small tacks, but adhesive is preferably used wherever possible. All exposed woodwork should be coated with dope and faced with the foil 105 in the same manner as the wood framework of the wings above described, but care should be used to see that the foil is laid smoothly. When all the exterior surfaces of the aircraft are thus covered with foil a 110

suitable coloring coat of dope or colored paint may be applied if the foil is too bright and shiny, and finally one or more coats of spar or other oil varnish are given to the 5 fireproofed parts.

The foil preferred for this method of fireproofing is aluminum foil of a gage about .0005 of an inch thick and measuring about 10,000 square inches to the pound. The paper 10 backing weighs about the same and can be easily stripped off from the foil. The foil may be backed with any other kind of paper or with cloth, and this foil is suitably prepared for use in this fireproofing 15 process and then put up in rolls for convenient handling. The foil is the main protection of the dope from fire. Therefore, the greater the risk of fire the thicker should be the foil, and it may be .001 of an inch 20 thick, or even thicker.

In preparing the foil the aluminum side is sprayed or otherwise covered with a stickum dope or other adhesive and then passed through a heated dry box, or an air-drying 25 system without heat. Several coats may be applied in this manner, any suitable mechanical means being employed for applying the adhesive. The foil thus coated is next perforated in a suitable perforating 30 machine with perforations, say, ten holes per square inch more or less, and each hole being about the size of a large pin hole. The only object of these perforations is to allow 35 air to escape between the foil and the surface to be covered while the foil is being laid. If the foil is applied slowly and with care fewer and smaller holes are required, but for quick work larger holes and more of them are desirable.

In lieu of or supplementary to using the 40 fireproofing liquid the linen or cloth before it is applied to the wings may have applied to it two or more coats of dope, and when dry, one coat of stickum, the coated foil is applied and the paper torn off, no varnish 45 being needed. After such treatment the fabric to which the foil is attached may be cut and sewed on the wing frame or other parts of the craft in the usual manner, using the foil side against the woodwork, and then the outer surface is doped and faced 50 with foil, according to the method above explained. This double facing of foil is used where extra fireproofing is required 55 for protection against bombardment of explosive gas shells. When foil-facing the linen in long lengths with foil, a doubling machine, commonly used in the rubber industry, may be employed.

The various aircraft dopes now in use are 60 affected by weather as well as by light, but by the use of foil in the manner herein described, air, light and weather have but little, if any, effect, and furthermore the fireproofing quality is materially improved.

Obviously other foils than aluminum may be employed, but aluminum is preferable, because of its weight. For example, an aeroplane containing 1,000 square feet of surface to be protected, which equals 144,000 70 square inches, requires about 7 pounds of foil of .0005 inch gage when the foil is applied to only one side of the cloth.

"Dope" is a customary trade name, but "stickum" dope is my preferred descriptive 75 appellation, and this stickum dope is prepared as follows:

To two parts of dope is added one part, more or less, of a shellac solution, such as seven ounces of orange or other shellac, and 80 one pint of denatured alcohol or other solvent.

In lieu of stickum dope there may be used for an adhesive ordinary orange or other shellac dissolved in methyl acetone 85 or other solvent.

Having thus described my invention, I claim as new and desire to secure by Letters Patent:

1. In a fireproof covering, a cloth, a covering 90 for the cloth including a slow burning substance and a metal foil disposed over the said covering.

2. A fireproof covering for the inflammable parts of aircraft and the like, including 95 a metal foil coated with an adhesive.

3. A fireproof covering for the inflammable parts of aircraft and the like, including 100 a perforated metal foil coated with an adhesive.

4. In combination with a part to be protected, of one or more coats of slow burning 105 dope thereon, and a covering of foil adhering to the said coated part.

5. The combination of an inflammable part to be protected, a coating of fireproof liquid dried thereon, a coating of dope dried on the first-mentioned coat, and a layer of 110 foil adhering to the second-mentioned coat.

6. The combination of an inflammable part to be protected, a coating of fireproof liquid dried thereon, a coating of dope dried on the first-mentioned coat, a layer of foil 115 adhering to the second-mentioned coat, and a coat of waterproof varnish on the foil.

7. The combination of an inflammable part to be protected, a coating of fireproof liquid dried thereon, a coating of dope dried on the first-mentioned coat, a layer of foil 120 adhering to the second-mentioned coat, one or more coats of dope on the surface of the foil, and one or more coats of waterproof varnish on the surface of dope.

8. In combination with an inflammable 125 part to be protected, a surface covering of a slow burning dope solution dried thereon, and layers of foil on both surfaces of the said part.

9. The method of fireproofing an inflam-

- mable part of an aircraft or the like which consists in applying a slow burning dope liquid thereto, drying the liquid, and covering the coated part with metal foil.
- 5 10. The method of fireproofing an inflammable part of an aircraft or the like which consists in applying a slow burning liquid thereto, drying the liquid, applying an adhesive to the coated part, applying a foil 10 with a removable backing thereon to the adhesive-covered surface and finally removing the backing from the laid foil.
- 15 11. The method of fireproofing an inflammable part of an aircraft or the like which consists in applying a slow burning liquid thereto, drying the liquid, applying an adhesive to the coated part, applying a foil with a removable backing thereon to the adhesive-covered surface, and removing 20 the backing from the laid foil and coating the foil with a waterproof varnish.
- 20 12. The method of fireproofing an inflammable part of an aircraft or the like which consists in applying a slow burning liquid thereto, drying the liquid, applying an adhesive to the coated part, applying a foil 25 with a removable backing thereon to the adhesive-covered surface, removing the backing from the laid foil, applying one or more coats of dope on the foil, and applying an outer layer of one or more coats of varnish.
- 30 13. The herein-described method of coating an inflammable part of an aircraft or the like, which consists in coating the part 35 with a fireproof liquid, drying the coating, applying a coating of dope, applying a coating of adhesive on the surface of dope, and applying a layer of foil on the adhesive.
- 35 14. In combination with a part to be protected, one or more coats of slow burning substance thereon, and a covering of perforated foil adhering to the said coated part.
- 40 15. In a fireproof covering, a cloth, a covering including cellulose acetate dope, 45 and a metal foil disposed over the said cellulose acetate dope.

PARKER R. BRADLEY.
